EXERCISER

William L. King, Springfield, Oreg., assignor to
Nathan E. Knecht, Springfield, Oreg.

Filed Mar. 9, 1970, Ser. No. 21,782

Term of patent 14 years

Int. Cl. D21—02

U.S. Cl. D34—5

Fig. 5

Fig. 4

FIG. 1 is a perspective view of the exerciser, showing my new design;

FIG. 2 is a top plan view of the article;

FIG. 3 is a bottom plan view of one side of the article (the opposite side being identical in appearance);

FIG. 4 is a side elevation of the article; and

FIG. 5 is a view taken generally along the line 5—5 in FIG. 4.

I claim:

The ornamental design for exerciser, as shown and described.
